UNITED STATES PATENT OFFICE.

HARRY H. MACNIVEN, OF BREEDSVILLE, MICHIGAN.

BRIDLE-BIT.

No. 882,791.

Specification of Letters Patent. Patented March 24, 1908.

Application filed August 3, 1907. Serial No. 386,965.

To all whom it may concern:

Be it known that I, HARRY H. MACNIVEN, citizen of the United States, residing at Breedsville, in the county of Van Buren and State of Michigan, have invented certain new and useful Improvements in Bridle-Bits, of which the following is a specification.

This invention has for its object a simple and efficient construction of bridle bit which will be durable and easy on the horse's mouth, the invention relating particularly to that type of bits which embody a covering of leather or are composed entirely of leather, the present invention consisting of a bit of this type which is composed entirely of leather except for a preferably spring steel stiffening bar which will provide for a slight spring to the bit and make it much easier on the horse than an iron covered bit.

10 The invention also consists in certain constructions and arrangements of the parts that I shall hereinafter fully describe and claim.

For a full description of the invention and the merits thereof and also to acquire a knowledge of the details of construction and the means for effecting the result, reference is to be had to the following description and accompanying drawings, in which:

Figure 1 is a perspective view of my improved bridle bit. Fig. 2 is a horizontal sectional view thereof. Fig. 3 is a transverse sectional view on the line 3—3 of Fig. 2.

Corresponding and like parts are referred to in the following description and indicated in all the views of the drawings by the same reference characters.

In the manufacture of my improved bridle bit, I take a stiffening bar 1, preferably of spring steel and place on either side thereof inner strips 2 of leather. An outer strip 3 is bent upon itself to embrace the two inner strips 2 and their inclosed stiffening bar 1, the ends of said outer strip being feathered and overlapped as indicated at 4 and the strip being looped or curved around the rein rings 5, as clearly illustrated in the drawings.

Preferably two rows of stitching are used to secure the strips together, said stitching being designated 6 and extending longitudinally of the bit on both sides and close to the 50 stiffening bar 1. Preferably the leather is rounded and finished, after being trimmed, by laying the bit in a specially designed mold the parts of which are pressed together so as to make the bit perfectly round and smooth 55 as well as hard and solid.

From the foregoing description in connection with the accompanying drawing, it will be seen that I have provided a very simple form of leather bit which embodies a spring 60 bar 1 which is for the sole purpose of stiffening the bit and rendering the same durable while at the same time it affords a slight elasticity to the bit and makes it easier on the horse's mouth than the ordinary iron cov- 65 ered bit; and also which embodies two leather strips between which the stiffening bar 1 is placed, and a continuous or one-piece outer strip which embraces the two inner strips 2 and which has its ends scarfed and over- 70 lapped so as to produce a uniform structure.

Having thus described the invention, what is claimed as new is:

The herein described bit, consisting of a spring stiffening bar, two strips on opposite 75 sides of said stiffening bar, a one-piece outer strip extending along the outer side of one of the inner strips and bent at intermediate points to form sockets for the rein rings, the ends of said outer strip extending along the 80 outer side of the inner strip and being scarfed and overlapped, and two rows of stitching extending through all of said strips, the said rows being located on opposite sides of the stiffening bar and close to the latter. 85

In testimony whereof I affix my signature in presence of two witnesses.

HARRY H. MACNIVEN. [L. S.]
